FIG. 1

Inventor:
Ira Vaughn
by Jas. H. Churchill
Attorney.

UNITED STATES PATENT OFFICE.

IRA VAUGHN, OF SALEM, MASSACHUSETTS, ASSIGNOR TO THE VAUGHN MACHINE COMPANY, OF PORTLAND, MAINE.

FINISHING-ROLL.

SPECIFICATION forming part of Letters Patent No. 546,868, dated September 24, 1895.

Application filed April 19, 1895. Serial No. 546,398. (No model.)

To all whom it may concern:

Be it known that I, IRA VAUGHN, residing in Salem, county of Essex, and State of Massachusetts, have invented an Improvement in 5 Finishing-Rolls, of which the following description, in connection with the accompanying drawings, is a specification, like letters on the drawings representing like parts.

This invention relates to a novel construction of roll for operating upon hides or skins, and is an improvement upon operating-rolls of the class shown and described in United States Letters Patent No. 274,859, dated March 27, 1883, and No. 344,069, dated June 22, 1886.

15 The operating-rolls shown in the patents referred to are provided with a plurality of substantially-long threads or flanges extending in opposite directions toward the ends of the roll, and with smaller flanges or threads 20 which extend from the main flanges or threads at an angle thereto. The long flanges or threads of the rolls shown in the patents referred to extend from a transverse line at the center or other point intermediate of the ends 25 of the roll and run or extend in opposite directions to the ends of the roll at the same or substantially the same angle. These rolls are now employed for unhauling, fleshing, putting out, stretching, &c., and are effective there-

30 for; but practice has demonstrated that when the hide or skin has been put through the putting-out machine—such, for instance, as shown and described in United States Patent No. 444,173, dated January 6, 1891—the hide

35 or skin is put out or stretched, but not in a satisfactory manner, owing to the fact that the stretch on opposite sides of the transverse line is in the same direction, and as the neck-and-shoulder portion of the hide is of a differ-

40 ent shape from the body portion the stretch of the neck-and-shoulder portion in the same direction as the body portion leaves in the hide or skin the original fullness or bag formed by the shoulders, whereas the original fullness 45 in the body portion formed by the hips of the animal is taken out.

This invention has for its object to provide a construction of operating-roll by which the bag or fullness in the neck-and-shoulder por-

tion of the hide, and which is left in the hide 50 or skin in the putting-out operation, may be taken out and the hide or skin further enlarged or stretched to the extent of such bag or fullness; and this operation, which is now performed by hand, I prefer to distinguish 55 from the putting-out operation by hereinafter referring to it as the "finishing" operation and to designate the improved roll as the "finishing-roll."

In accordance with this invention the finishing-roll is provided with two sets of vanes, flanges, threads, or blades extended spirally in opposite directions from or about a transverse line through the roll, preferably at or about two-thirds its length, the short set of 65 vanes being extended at a different angle from the long set of vanes and each short vane preferably having its co-operating long vane, whereby the body of the hide or skin is stretched and smoothed in one direction by 70 all the long vanes and the neck and fore part of the hide or skin are stretched and smoothed out in an opposite direction by all the shorter vanes, but at a different angle, which takes out the bag or fullness formed by the shoulders. 75

Figure 1 is a plan view of a pair of finishing-rolls embodying this invention; Fig. 2, end elevations of the rolls shown in Fig. 1, and Fig. 3 an outline of a hide to more clearly illustrate the operation of the finishing-rolls. 80

In the present instance two finishing-rolls A A' are shown, which in practice are and may be substituted for the putting-out rolls shown in the Patent No. 444,173, above referred to, and the machine thus changed may 85 be used for finishing the operation on the hide or skin performed by the putting-out machine.

The finishing-rolls A A' are of like construction, and each roll is provided on its periphery with two sets of spirally-arranged vanes, 90 blades, flanges, or threads a a', extended from a transverse line or plane through the roll toward its opposite ends, but at different angles with relation to said transverse line or plane.

The transverse line or plane referred to in 95 the present instance is located substantially one-third the length of the roll from one end of the same, the long vanes a being substan-

- tially twice as long as the short vanes a' . The transverse line or plane through the finishing-roll corresponds substantially to the line x x , Fig. 3, and the long vanes a act on the body portion 2 of the hide or skin, while the short vanes a' act on the shoulders and neck portion 3 of the hide or skin, but the stretching action of the short vanes a' is at a different angle from the long vanes a , and 10 this action of the finishing-roll on the hide or skin may be better understood by supposing that the long vanes a stretch the body portion of the hide or skin in the direction indicated by the arrow 20, Fig. 3, and that the short 15 vanes a' stretch the shoulders and neck portion in the direction indicated by the arrow 22. The long vanes a , it will be noticed, wind about the roll and have less pitch than the short vanes a' . 20 It will be understood that the vanes not only are to lengthen the hide or skin, but are to widen at the same time. 25 It will be noticed that in the finishing-roll herein shown each long vane or blade a has its co-operating short vane or blade a' , so that the two vanes or blades approximate one continuous vane or blade extended from end to end of the roll, but in opposite directions from a transverse plane or line through the 30 roll and in different angles with respect to said

plane and to each other, which is the construction I prefer to use.

I claim—

1. A finishing roll provided with two sets of vanes or blades extended in opposite directions from a transverse line or plane through the roll and at different angles thereto and to each other, for the purpose specified. 35

2. A finishing roll provided with the long vanes a and with the shorter vanes a' extended 40 in opposite directions at different angles, the long vanes being located on one side of a transverse line through the roll, and the short vanes being located on the other side of said transverse line, and each long vane having its 45 co-operating short vane, substantially as and for the purpose specified.

3. A finishing roll provided with two sets of vanes or blades extended in opposite directions from a transverse line or plane through 50 the roll, one set of vanes having a different pitch from the other set of vanes, substantially as described.

In testimony whereof I have signed my name to this specification in the presence of 55 two subscribing witnesses.

IRA VAUGHN.
